UNITED STATES PATENT OFFICE.

RAYMOND L. LUNT AND FRANK M. HENRY, OF MINNEAPOLIS, MINNESOTA, ASSIGNEES
TO THE HI-POWER COMPANY, OF MINNEAPOLIS, MINNESOTA, A CORPORATION OF
SOUTH DAKOTA.

SUPERHEATED-STEAM EQUIPMENT FOR INTERNAL-COMBUSTION ENGINES.

Application filed October 8, 1920. Serial No. 415,571.

To all whom it may concern:

Be it known that we, RAYMOND L. LUNT and FRANK M. HENRY, citizens of the United States, residing at Minneapolis, in the county of Hennepin and State of Minnesota, have invented certain new and useful Improvements in Superheated-Steam Equipment for Internal-Combustion Engines; and we do hereby declare the following to be a full, clear, and exact description of the invention, such as will enable others skilled in the art to which it appertains to make and use the same.

Our invention relates to internal combustion engines and is directed to the provision of simple and efficient means for supplying superheated steam and commingling the same with the explosive charges, within the engine cylinders.

Generally stated, the object of our invention is to increase the efficiency of the engine in point of high power, running economy and reliability.

In accordance with our invention, we accomplish the above objects by the provision of a flashing plate placed entirely within the explosion chamber of the cylinder and against which superheated steam is discharged. This flashing plate is secured from the cylinder head at the compression end thereof; is spaced from said head so that it will be substantially surrounded by hot gases; is connected to the cylinder head or head end of the cylinder by a small neck, the heat-conducting capacity of which is not great; and the superheated steam is delivered directly against this flashing plate.

The invention is illustrated in the accompanying drawings, wherein like characters indicate like parts throughout the several views.

Referring to the drawings:

Fig. 1 is a side elevation showing a multi-cylinder internal combustion engine having our improved steam superheater applied thereto;

Fig. 2 is a plan view of said engine and superheater, some parts being broken away; and

Fig. 3 is an elevation with some parts sectioned on the line 3—3 of Fig. 2.

The engine illustrated is of the usual construction, but, as shown, is a six-cylinder engine, and hence, the parts thereof may be

briefly noted as follows: the crank chamber 4, cylinder block 5, fly-wheel 6, spark plugs 7 and exhaust manifold 8.

The arrangement of admission and exhaust manifolds, valves and the like, may be the same in the engine illustrated as those of any standard multi-cylinder engine.

In carrying out our invention, we preferably use approximately one-half as much water as gasoline or hydrocarbon fuel, and this water may be supplied from a suitable tank 9* which has a discharge pipe 9 that will be connected, through a suitable valve mechanism, to a steam-generating tube 10 that is extended through or within the exhaust manifold 8. The valve mechanism just referred to, may take various forms, but, as shown, is an ordinary carbureter indicated as an entirety by the numeral 11. Here, said carbureter 11 will act as a spraying device to deliver water vapor into the steam-generating tube.

The tube 10, as shown, is extended out through one end of the exhaust manifold 8 and is connected to a steam manifold 12 located over the top of the engine and provided with branch pipes 12^a, there being one of the latter for each cylinder of the engine. Each branch pipe 12^a is connected, by an elbow 13, to the upper end of a fixed tubular stem 14 that is extended downward through the top of the respective cylinder, into the explosive chamber thereof, and, at its inner end, has an expanded shoulder 15, against which a concavo convex disk-like flashing plate or flange 16 is clamped, by a nut 17 threaded on the extreme inner end of said stem. The flashing plate 16 is preferably of copper and is provided with a multiplicity of holes to prevent the same from being bent or distorted by the force of the explosions. The stem 14 has a small axial passage 18, which, at its lower extremity, is laterally extended so that it leads outwardly through the shoulder 15. Interposed in the several branch pipes 12^a are check valves 19 that permit flow of superheated steam from said branch pipes into the respective cylinders, through the axial passage 18 of the corresponding stem 14, but checks the reverse or backward flow when the explosions take place and at all other times.

The steam-generating tube 10 is prefer-

ably a nickel-steel tube. When the engine is in action, the nickel-steel steam-generating tube 10 will be heated to a high temperature and the copper disk 16 will be kept 5 at a dull red heat, but will not be raised quite to the flashing point of the explosive vapor, and, hence, will not produce premature explosions. The heat from said disk will be quite rapidly conducted therefrom 10 through the stem 14, thus preventing overheating thereof. As will presently appear, the copper disk-like plate 16 performs an important function, which entitles it to be designated as a flashing plate. Said plate 15 may, however, take various different forms, but to obtain the best results should be so arranged and located that the superheated steam delivered into the cylinder will be delivered directly against the same.

20 The summary of the operation is substantially as follows:

The water admitted into the generating tube 10 will be quickly converted into steam and then into superheated steam, and will 25 be delivered through the steam manifold 12 and its branch pipes and stems 14, directly into the cylinders and against the atomizing plates 16.

Obviously, the superheated steam will be 30 drawn into the cylinders under the suction strokes of the respective pistons. If, at any time, the pressure produced by the superheated steam in the generating tube 10 exceeds the force produced by suction, 35 the further supply of water vapor, in said generating tube, will be automatically but temporarily stopped, to be again resumed whenever the suction force exceeds the back pressure of the generating steam in said 40 tube.

The tube 10, above designated as a steam generating tube, is one form of steam generating chamber and is located in the exhaust manifold or so arranged that it is 45 heated by the exhaust from the engine. The arrangement of any form of steam generating chamber, in the manner above indicated and connected to the cylinders by a steam manifold, is considered broadly new.

50 The heat cycle is substantially as follows:

The hot gases from the exhaust manifold, acting on the tube 10, raise the temperature thereof nearly to that of the hot gases, and this tube abstracts an extremely large 55 amount of British thermal units (B. t. u.) contained in the hot gases, and the heat thus abstracted will be absorbed by the water in the tube 10 and, in latent form, will be carried into the cylinders, by the superheated steam.

When the superheated steam strikes the 60 flashing plates 16, any heat that has been lost by radiation is restored therein and the reactions above noted will take place, 65 thus increasing the intensity of the explo-

sion. Moreover, as already indicated, the introduced steam not only intensifies but prolongs the time of action of the force of the explosion on the piston, so that, somewhat, the action of a steam engine is added 70 to or combined with that of the internal combustion engine. It will thus be seen first that the salvage of heat units from the exhaust and then the introduction thereof back into the cylinders, must increase the 75 efficiency of the engine. It also makes possible the use of low grade hydrocarbons, such as kerosene, which are known to be richer in heat units than the higher grade hydrocarbons, without encountering the usual results by way of accumulations of carbon in the cylinders on the pistons. The elimination of carbon deposits in engines, in itself, is of such known advantage that it does not require elaborate discussion.

80 What we claim is:

1. The combination with an internal combustion engine, of a flashing plate of less diameter than the engine cylinder located entirely within the explosion end of the engine cylinder, means outside of the engine cylinder for generating steam, and means for delivering steam thus generated against said flashing plate while the latter is hot.

2. The combination with an internal combustion engine, of a flashing plate of less diameter than the engine cylinder rigidly supported in the explosion end of the engine cylinder adjacent to the head thereof and substantially surrounded by the explosion space of said cylinder but having a contracted tubular neck extended through the cylinder, and means for delivering vaporized water or steam through said neck and directly against said flashing plate.

3. The combination with an internal combustion engine, of a flashing plate of less diameter than the engine cylinder rigidly supported in the explosion end of the engine cylinder adjacent to the head thereof and substantially surrounded by the explosion space of said cylinder but having a contracted tubular neck extended through the cylinder, and a steam generating tube subject to heat from the engine exhaust and connected to the tubular neck of said flashing plate for the delivery of steam directly against said flashing plate.

4. The structure defined in claim 1 in which said flashing plate is perforated for the free passage of gasses therethrough.

5. The structure defined in claim 3 in which said flashing plate is cup-shaped, is perforated, and the steam is delivered directly onto the upper surface thereof.

In testimony whereof we affix our signatures.

RAYMOND L. LUNT.
FRANK M. HENRY.
